(57) **CLAIM**

The ornamental design for a pull cord positioning device for a window curtain, as shown and described.

DESCRIPTION

FIG. 1 is a perspective view of a pull cord positioning device for a window curtain;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a rear perspective view of the device and shows the device being mounted on a wall and a pull cord being installed in the device, the broken line forming the pull cord and the wall forming no part of the claim.
